FOOT COVERING

Anne Yandell, New York, N. Y.

Application October 29, 1943, Serial No. 508,161

4 Claims. (Cl. 36—10)

This invention relates to a structurally and functionally improved foot covering. According to one of its more specific aspects, it aims to provide an improvement over the structure and technique generally disclosed in my prior application for United States Letters Patent filed on April 10, 1943, and identified under Serial Number 482,562.

It is an object of the invention to provide a foot covering or enclosing structure of improved design which may be utilized or worn in any desired manner but which will preferably be disposed between the foot and the shoe of the wearer. Also, if the wearer is dressed in stockings, the present device will preferably be interposed between the stocking and the encasing shoe.

A further object is that of providing a unit of this type and which will remain in position upon the foot of the wearer and free from any tendency to ride down and under the heel or upwardly along the same to an extent such that it would result in discomfort.

Another object is that of furnishing a foot covering which will achieve results such as are traversed in the foregoing objects and which, at the same time, will embody a relatively simple construction capable of being readily manufactured. Accordingly, a unit may be produced which may be sold at a relatively nominal figure.

With these and other objects in mind, reference is had to the attached sheet of drawing illustrating practical embodiments, and in which:

Fig. 1 is a face view of a blank from which the foot covering may be produced;

Fig. 2 is a perspective view of a partially assembled foot covering provided by this blank;

Fig. 3 is a side elevation of the unit and showing the same in applied position on the foot of the wearer;

Fig. 4 is a view similar to Fig. 1 but illustrating an alternative form of blank;

Fig. 5 is a perspective view of a member constructed from the blank shown in Fig. 4; and

Fig. 6 shows that member in applied position upon the foot.

Referring primarily to Fig. 1, it will be seen that the reference numeral 10 indicates the body of the blank which may be formed of any suitable material. Preferably, however, it is knitted or woven of a material similar to that employed in the manufacture of stockings. As illustrated, the front edge of the blank may include projecting portions 11, 12 and 13, each preferably defined by curved edges. The projecting portion 11 defines that portion of the unit which is to underlie

or extend substantially adjacent the toes of the wearer; the portion rearwardly of such projection underlying the sole of the foot and terminating in a part 14 which lies adjacent the heel of the wearer.

To each side of the rear portion 14, portions 15 and 16 may project. The rear edges of the latter preferably extend outwardly and join in an outward direction with the side edges of the blank. These side edges 17 preferably extend slightly toward each other in the direction of the forward end of the blank. As will be seen, preferably straight edge portions 18 extend rearwardly of portion 14.

As illustrated in Figs. 2 and 3, one of the projecting portions 13 is folded upon the central projection 11 and these parts are attached along their respective peripheries in any desired manner as, for example, by stitching. This stitching may, of course, be of the "blind" type so that the unit may be reversed if desired. The second and outer projecting portion adjacent the forward edge of the blank is now folded over to overlap the first portion as well as the central projection 11 and is similarly stitched thereto about the forward edges thereof. It will be understood that the stitching of the respective elements may be done at one time, if desired. As a consequence of this construction, a toe-enclosing portion is furnished. Also, if a rearward strain or pull is exerted upon those parts of the unit which extend to each side of the part underlying the foot sole, it will be found that the overlapping portions are placed in a condition of tension. This has the result that the toes are firmly—but not bindingly—enclosed and a self-sustaining structure is presented when the covering is applied to the foot.

In order to achieve this result, the end edges defining the projections 15 and 16 are again connected by stitching or otherwise. Thus, a heel portion is furnished which will snugly engage the heel adjacent its base and thus exert a tension throughout the entire structure and in order to achieve the aforementioned effect. The line of connection between the projections 15 and 16 has been indicated by the reference numeral 19 as in Fig. 2. As will also be clearly seen in this figure, no stitching or equivalent method of connection is provided between this heel-encircling portion and the relatively projected part 14 which underlies the heel. Accordingly, a gap 20 is furnished at this point.

It is found, as a result of this construction, that any tendency of the foot covering to ride

downwardly around the heel is prevented. In effect, one might state that a strap portion is furnished which, as the wearer's foot flexes, tends to ride upwardly around the rear of the foot. However, such tendency will never occur to the extent that a binding of the parts results; this being precluded because of the general design of the unit and also the material of which it is preferably formed.

Now referring to the construction of the blank shown in Fig. 4, it will be seen that the body of this member is in most respects similar to the body 10 as shown in Fig. 1. Forward projections 21, 22 and 23 are provided, and the configuration of these may correspond to the configurations of projections 11, 12 and 13 or be modified if desired. The side edges of the blank are also substantially identical with the side edges as illustrated in Fig. 1. However, the rear edge of the blank is formed with a recess 24 which is centrally disposed and which extends well into the sole portion of the covering. To each side of this recess, projecting portions 25 and 26 are provided. These may be relatively narrow and their rear edges may be cut to extend at a tangent.

The toe portions of the blank as illustrated in Fig. 4 may be assembled in precisely the manner described in connection with the blank of Fig. 1. It will be seen, however, that the projections 25 and 26—when their end edges are connected—provide in aggregate what might be truly termed a strap. As shown in Fig. 6, this strap rides or bears against the rear of the wearer's heel.

In such position, it will preferably lie above the lower portion of the heel. Consequently, it will not tend to ride downwardly over the heel. It will also be apparent that, as a consequence of the recess or notch 24, the heel proper or that portion of the foot covering which underlies the heel of the foot sole is entirely eliminated as indicated by the reference numeral 27. It follows that any tendency of the covering member to ride under the heel will thus be prevented to even a further extent. At the same time, a condition of tension will be imparted to the portions of the unit and such that it will snugly embrace the adjacent part of the foot.

Thus, it will be seen that in both of the illustrated forms of the foot covering a unit is presented which includes a sole-engaging portion having its forward-end terminating in what might be termed a projection. To each side of this portion material parts are presented which, when the blank is assembled, furnish side walls. The forward ends of the latter also terminate in projections. These are caused to overlap each other and also the projections of the toe portion, and the parts are secured in position by stitching of any suitable type or in any other desired manner. The rear ends of these side walls are preferably cut to extend outwardly. Consequently, when these ends are connected to form a heel-encircling member, they will not tend to ride downwardly around the heel and, in effect, a strap member is furnished. The lower edge of this latter member is not connected to the adjacent sole portion. Consequently, as in Fig. 2, a slight gap or slit 20 results. In the structure of Figs. 4 to 6 where the heel portion of the sole has been eliminated, the slit is, of course, expanded to in effect furnish a relatively large opening 27. In both forms of structure, a collapsible (i. e., non-self-sustaining) unit is furnished which will maintain the proper position of its

several parts when applied to the foot of the wearer. Of course, a stiffening element or elements might be incorporated in the structure but this is usually unnecessary.

From the foregoing, it will be appreciated that, among others, the several objects of the invention as specifically afore noted are achieved. Obviously, numerous changes in construction and rearrangements of the parts might be resorted to without departing from the spirit of the invention as defined by the claims.

I claim:

1. A foot covering formed from a single piece of light, resilient, fabric, comprising a central sole-providing portion terminating at its forward end in an arcuate extension having a maximum width and length sufficient to underlie the toes of the wearer the rear end of said sole portion terminating forwardly of the heel of the wearer; relatively narrow side portions each terminating at its forward end in an arcuate extension substantially similar in length and width to said first-named extension, the rear edge of each said side extension curving sharply outwardly from the edge of its associated side portion and being materially wider than its associated side portion, said side portions extending rearwardly of said sole portion to provide strap members connected to said sole portion only at their forward ends, each of said arcuate side extensions being folded over each other and permanently secured to the first-named extension in overlapping relationship therewith to form a toe covering, and said strap members being connected at their rear free ends to encircle the heel of the wearer.

2. A stocking foot of inherently elastic fabric comprising a sole having a substantially semicircular toe end, a heel portion, and low side portions, each side portion having a substantially semicircular forward extension, the rear edge of which extends sharply angularly outwardly from the outer edge of its associated side, said extensions crossing each other in overlapping relationship and being secured to said semicircular toe end along substantially the full periphery thereof, the inner edge of each such extension making a relatively large angle with respect to the longitudinal axis of the sole, whereby the resilient tension afforded by the securement of the respective forward extensions to the toe end draws the sides and heel snugly about the foot of the wearer.

3. A blank of flat resilient fabric for forming a stocking foot, comprising a sole portion having a substantially semicircular toe end, and narrow extensions laterally on both sides of the sole portion flaring sharply outwardly at the toe end into substantially semicircular portions of substantially the same shape as the toe end portions of the sole.

4. A blank of flat resilient fabric for forming a stocking foot, comprising a sole portion having a substantially semicircular toe end and extending rearwardly substantially only to the arch of the foot, narrow extensions laterally on both sides of the sole portion flaring sharply outwardly at the toe end into substantially semicircular portions of substantially the same shape as the toe end portion of the sole, and relatively narrow bands extending rearwardly from each of said side extensions and having a length whereby said bands may be secured together at their free ends to provide a heel-encircling strap.
